UNITED STATES PATENT OFFICE

160,468

AUTOMOBILE ORNAMENT OR SIMILAR ARTICLE

Eric Berggren, Chicago, Ill., assignor to Blackstone Manufacturing Co., Inc., Chicago, Ill., a corporation of Illinois

Application March 27, 1950, Serial No. 8,803

Term of patent 14 years

(Cl. D14—18)

To all whom it may concern:

Be it known that I, Eric Berggren, a citizen of the United States, residing at Chicago, in the county of Cook and State of Illinois, have invented a new, original, and ornamental Design for an Automobile Ornament or Similar Article, of which the following is a specification, reference being had to the accompanying drawing, forming part thereof.

Figure 1 is a front view of an automobile ornament or similar article, showing my new design,

I claim:

The ornamental design for an automobile ornament or similar article, as shown.

ERIC BERGGREN.
